ALEXANDER W. LIMONT, OF BRIDGEPORT, CONNECTICUT, ASSIGNOR TO BRIDGEPORT BRASS COMPANY, OF BRIDGEPORT, CONNECTICUT, A CORPORATION OF CONNECTICUT.

CAP FOR ELECTRIC-LIGHT SOCKETS.

1,396,857.

Specification of Letters Patent. Patented Nov. 15, 1921.

Original application filed February 10, 1915, Serial No. 7,291. Divided and this application filed August 26, 1915. Serial No. 47,522.

To all whom it may concern:

Be it known that I, ALEXANDER W. LIMONT, a citizen of the United States, residing in Bridgeport, county of Fairfield, and State of Connecticut, have invented certain new and useful Improvements in Caps for Electric-Light Sockets, of which the following is a full, clear, and exact description.

This invention relates to the metal caps of electric light sockets or shells, which are commonly known as socket caps. As ordinarily constructed, these caps consist of at least three separate parts, to wit: a shell or cap proper constructed of light sheet metal; a relatively heavy hub or bushing, having a threaded bore; and a washer, by means of which the hub is clenched or staked to the shell. This construction, however, has the drawback that notwithstanding the exercise of considerable care, it will usually be found that of a given number of caps manufactured by the customary operations, some are defective owing to the looseness of the connection between the hub and the shell. Then again, even if the hubs are tightly locked to the shells when the articles leave the factory, the parts are very apt to work loose if they are subjected to slight strains. Furthermore, with the ordinary construction, the shell itself is quite weak at or near the juncture with the hub or bushing, and this causes the shell to crack when it is subjected to a comparatively slight strain.

One of the objects of my invention is to provide an improved form of socket cap in which the above-mentioned defects are eliminated. Another object of the invention is to furnish a simple and efficient socket cap in which the shell and hub are integral with each other, being stamped from a single metal blank, and wherein, nevertheless, the hub has a wall of sufficient thickness to carry a cut thread without buckling under the stresses to which it is subjected. Furthermore, in accordance with my invention, the entire shell or cap proper may be made from the same piece of metal as the hub and it may be so designed as to combine maximum lightness with maximum resistance against cracking or splitting at the zone of special strain.

To these and other ends, the invention consists in the novel features and combina-

tions of parts to be hereinafter described and claimed.

55

In the accompanying drawing, Figure 1 is a perspective view of a socket cap constructed in accordance with my invention.

Fig. 2 is a vertical section of the cap. 60

Fig. 3 is a detail of the blank.

Figs. 4 to 8 inclusive show the blank at different stages in the process of manufacture; and

Fig. 9 shows one stage in a somewhat modified process of manufacture.

Referring particularly to Figs. 1 and 2, my improved socket cap comprises a dome-shaped shell 10 of sheet or wrought metal, and a hub or bushing 11 integral therewith, at the summit of the dome and having a bore provided with interior screw threads 12. At its free edge, periphery or rim the shell is usually provided with the flange or offset 13 which is formed as an integral part thereof. 75 In the particular form shown, the wall of the hub 11 is quite thick relative to that of the shell and the threads 12 are cut in the wall of the hub, or in other words, they are formed by the usual tapping operation. At 80 and near its juncture 14 with the hub, the wall of the shell is thicker than at the peripheral portion of the shell so as to reinforce the line or zone of juncture and make it thick and strong enough to resist the 85 strains to which it is subjected. In the particular example illustrated, the cross-sectional area of the shell wall is progressively increased from the rim to the juncture with the hub. In the ordinary use of the device, 90 the rim portion is subjected to much less strain than the juncture between the shell and hub and it will be apparent that my construction meets this condition in a very effective way.

95 In making the cap I use as a blank a flat disk 15 of brass or other metal, which is preferably quite thick, say, .105 gage, and of less diameter than that of the socket cap to be constructed. This blank 15 is placed in 100 a suitable die 16 (Fig. 4) and cupped by means of a punch 17. The center part of the blank is thus formed with a shallow, gradually curved cup or boss 18 and the cross-section of the bottom of the cup or 105 boss is somewhat reduced as compared to the

initial cross-section. The blank is then transferred to a die 19, as shown in Fig. 5, and is formed by means of a punch 20 coöperating with said die. The die 19 is provided with a depression or recess 19^a of less diameter than the blank resulting from the operation shown in Fig. 4, and this depression or recess 19^a has a substantially flat bottom and an upright, substantially cylindrical side wall. The punch 20 carries a projection 20^a adapted to enter the recess 19^a with a considerable amount of clearance at the periphery of the recess, and surrounding the recess 19^a is a flat stamping surface 19^b on the die adapted to coöperate with a similar flat stamping surface 20^b on the punch surrounding the projection 20^a. When the blank resulting from the operation shown in Fig. 4 is formed by the punch and die shown in Fig. 5, a substantially cylindrical boss 21 of relatively small diameter is formed on the blank. The blank then has the peculiar characteristic that the side wall of the boss 21 formed by this operation is thicker than any other part of the blank, that is, the cross-section area of said wall is greater than that of the flat outer or brim portion of the blank and greater than the cross-section of the bottom of the boss 21. The substantially cylindrical wall of the boss 21 preferably approximates the original blank in thickness. At the same time, the flat outer portion of the blank is made very much thinner than the original blank. As the punch 20 descends on the blank resulting from the operation shown in Fig. 4, the outer or peripheral portion of the blank is flattened out considerably by the coöperating surfaces 19^b, 20^b of the die and punch, but nevertheless, while the unconfined outer peripheral portion is being forced out laterally to thin the same and increase the diameter of the blank, that portion of the punch surrounding the projection 20^a forces or displaces the adjacent metal inward and down into the recess 19^a to form the thick wall 21 previously mentioned. To accomplish this end, the punch projection 20^a joins the stamping surface 20^b on an easy curve or fillet and the die is shaped correspondingly. Furthermore, at the same time that the punch is forcing metal inwardly and downwardly into the recess 19^a to form the thick wall 21, said punch is also forcing metal upwardly into the wall 21 from the bottom of the boss. This is accomplished by designing the punch and die so that when the punch is moved to its lowest position, the lower surface of the projection 20^a presses very forcibly the metal between it and the bottom of the recess 19^a so as to flow or displace such metal outwardly in a radial direction and upwardly around the side surface of the projection 20^a.

65 It will be understood, therefore, that the

operation shown in Fig. 5 consists of flattening out and thinning the outer or peripheral part of the blank shown in Fig. 4, thereby increasing the diameter of the blank; and in forming at the center portion of the 70 blank a boss having a thick side wall, by flowing or displacing metal outwardly and upwardly from a zone at and near the center of the blank, and flowing or displacing inwardly and downwardly a certain amount of 75 metal located in another zone more remote from the center of the blank.

After the forming operation shown in Fig. 5 is completed, the blank has its flat brim further thinned out as shown in Fig. 6 without, however, materially changing the shape of the boss 21. This may be effected by placing the blank in a die similar to the die 19 and using a punch similar to the punch 20, but having a centering projection of less 85 depth than the projection 20^a. In this operation one or more sharp quick hammer-like blows of the punch are required. The blank shown in Fig. 6 is then subjected to the operation shown in Fig. 7 for the purpose of shaping the flat brim portion into a dome-shaped shell. For this purpose, the die 22 (Fig. 7) is provided with a recess 23 to receive the boss 21 and with a curved wall 24 to give the brim portion the required 90 shape. The punch 25 comprises a plunger 26 adapted to fit the curved recess 24 of the die and carrying a centering projection 27 adapted to force the boss 21 into the recess 23, without, however, effecting any material 95 change in the shape of said boss. The punch 25 also comprises an independently movable member 28 which descends in advance of the plunger 26 and yieldingly holds the peripheral part of the brim of the blank during 100 the initial portion of the forming operation so as to prevent the blank from crimping, creasing or buckling. As the punch 26 is moved to its lowest position, the blank is drawn into the shape illustrated in dotted 105 lines in Fig. 7. The blank is then removed from the die, and acted upon by another punch and die which are generally similar to those shown in Fig. 7, but are so shaped as to perfect the form of the shell or dome 110 portion 10 of the blank and form the flange 13 on the periphery thereof, as shown in Fig. 8. The drawn socket cap is then completed by cutting out the bottom of the boss 21, (thereby creating the hub 11), tapping the 115 bore of the boss or hub with the threads 12, and forming the customary small tapped opening 29 in the wall of the hub.

It will be observed that the thick hub of the one-piece socket cap merges into the 120 dome without any distinct line of juncture, which is a factor of considerable importance in producing a cap of maximum strength and efficiency. The metal of the dome is gradually increased in thickness as the di- 130

ameter of the dome decreases, so as to produce a zone of juncture between the hub and dome which is of intermediate thickness. The hub and dome are preferably joined together by external and internal fillets so that the zone of juncture is not interrupted or cut into by a sharp angle at the outside of the cap. By joining the dome and hub on or with an external curve or fillet, the zone of juncture is not weakened and at the same time the polishing of the cap can be accomplished more easily than heretofore.

It will be understood that intermediate the several operations above described, the blank will be annealed to soften the same, and permit further stretching of the metal without breaking, and that it will be subjected to the usual pickling operations for thoroughly cleansing the same. Furthermore, it will be evident that the total number of forming or drawing operations may be varied, as called for by conditions, and the sequence of certain operations may likewise be varied without departing from the scope of the invention. Furthermore, so far as concerns the broad aspect of the process of making the socket cap, it is not essential that the thick wall of the hub be formed by flowing or displacing the metal both in an inward direction and an outward direction relative to the center of the blank.

In Fig. 9, I have illustrated another step of a somewhat modified method of forming the cap. According to this modification, I begin with a thinner blank of, say, .050 gage, and form a substantially cylindrical boss 30 directly thereon by means of a punch 31 and die 32. In this operation, the metal is flowed or displaced inwardly or downwardly, and also upwardly and outwardly around the projection 33 on the punch, substantially as previously described. The brim portion of the blank in this case only has to be flattened out to a slight extent, and therefore the periphery of said brim portion is confined in the manner shown, by an upright wall 34. Although it might appear that by starting with a thinner blank, the process previously described could be somewhat shortened, the fact is that in carrying out the operation shown in Fig. 9, the comparatively large superficial area of the blank reduces to a considerable degree the pressure per unit of area. The operation is less satisfactory, therefore, than that first described, according to which heavy pressure is distributed

over a small blank area in forming the blank during the initial stages.

It will be noted from Fig. 2, that in the particular example shown, the hub is more than twice as thick as the average thickness of the dome, and that the peripheral flange on the dome is not more than one-third the thickness of the main part of the hub. The hub is at any rate much thicker than the major portion of the dome and the lines of the hub flow into those of the dome on a curve or fillet at the exterior.

Various changes can be made in the form of the socket cap, and the method of producing same, without departing from the invention as defined in the claims. Moreover, it will be obvious that the cap need not in all cases be used for the specific purpose stated.

I do not claim herein the method of making the socket cap, as such subject matter is claimed in my application, Serial Number 7291, filed February 10, 1915, of which the present application is a division.

What I claim is:

1. A sheet metal socket cap such as described, comprising a drawn one-piece dome and hub, the hub being considerably thicker than the major portion of the dome and gradually merging into the dome at the summit of the latter by a zone of intermediate thickness.

2. A sheet metal socket cap, comprising a drawn one-piece dome and hub, the hub being considerably thicker than the main part of the dome and gradually merging into the latter on a fillet at the summit of the dome.

3. A socket cap or similar article such as described, comprising a drawn one-piece dome and hub of sheet metal, the peripheral portion of the dome being much thinner than the hub and gradually tapering into the latter on a fillet at the summit of the dome.

4. A drawn sheet metal one-piece socket cap, comprising a thin dome-shaped sheet metal shell and a substantially cylindrical wall at the summit of said shell merging therewith and constituting a hub, said wall being of considerably greater thickness than the shell and merging with the latter by a zone of intermediate thickness, said shell gradually decreasing in thickness from the hub to the periphery of the shell; substantially as described.

In witness whereof I have hereunto set my hand on the 16 day of August, 1915.

ALEXANDER W. LIMONT.
